UNITED STATES PATENT OFFICE.

GUSTAVE A. OVERSTROM, OF PASADENA, CALIFORNIA.

VIBRATING SCREEN.

Application filed September 28, 1920. Serial No. 413,376.

My invention relates particularly to screens where a very high frequency of vibration is employed to accomplish the desired results.

5 My object is to provide a vibrating screen box, in which all of the screen is effective screening surface, thereby using up the minimum of screen cloth, and in which as many different sized products as may be desired 10 can be made.

Another object is to provide the most simple and efficient flexible supporting means to this screen box, so as to allow of it being vibrated without transmitting the vibrations to the structure on which the apparatus is supported.

15 A further object is to provide a screening apparatus which is practically noiseless, easy to erect and repair, and which will 20 produce no wrecking action on the screen cloth.

Another object is to provide an effective and simple vibrating means, capable of being driven by any available power, at a high 25 rate of speed, and which will even on a level, move the material forward.

A still further object is to provide a vibrating screening apparatus which is not sensitive to accidental overload, but which 30 has a surplus of power available in case of need.

Another object is to produce a combination of vibrating means, screen supports, and stretching means, that are extremely 35 flexible in their combinations and application thereby suiting any conditions that may be presented.

Other objects will appear in the specification and description of my invention.

40 In carrying out my invention I provide, generally stated, a vibrating screen box in which one or more screens are stretched tight. The box is supported on springs which are fastened to rigid supports. These 45 springs allow of the frame being vibrated in a vertical plane. The vibrations are produced by the revolutions of a fast running unbalanced pulley, that revolves on a hollow shaft rigidly fastened to the screen box.

50 The pulley has oil chambers at both ends. Oil under strong centrifugal pressure is circulated by means of stationary scoops, from the revolving oil chambers to the run-

ning surfaces, and back to the chambers again.

55 The oil pressure thus produced, distributed over the whole effective bearing surface, is greater than the pressure produced by the revolving unbalanced pulley, thereby insuring a cool running and lasting oil floated bearing.

The material is advanced from the head to the tail of the screen by the combination of the spring supports and the direction of revolution of the pulley, which must revolve 60 in the same direction as the desired travel, looking down on the top of the pulley.

In the drawings accompanying this specification and forming a part thereof, Figure 1 is a plan view of one type of my vibrating 65 screen.

Figure 2 is a vertical longitudinal section taken on line 2, 2 of Fig. 1.

Fig. 3 is a side elevation.

Fig. 4 is a transverse section on line 4, 4, 70 Fig. 3.

Fig. 5 is a transverse section on line 5, 5, Fig. 3, the pulley and shaft shown full view.

Fig. 6 is a section through the oil chamber on line 6, 6, Fig. 5.

Fig. 7 is a cross-section through the unbalanced parts of the pulley.

Fig. 8 is an enlarged end view of one of the springs which support the screen box and 85 allow it to vibrate.

Fig. 9 is a longitudinal section through the pulley, the shaft being shown full.

Fig. 10 is a transverse section through the oil chamber on line 10, 10, Fig. 9.

Fig. 11 is a transverse section of the pulley on line 11, 11, Fig. 9, showing both the permanent and the adjustable unbalanced weight.

Figs. 12, 13 and 14 illustrate a modified 90 construction of pulleys in which the two oil chambers have communication through the body of the pulley.

Fig. 15 is a longitudinal section through a pulley and oil chambers used on large and 100 wide screen boxes, illustrating also the weights placed 180 degrees apart.

Fig. 16 is a cross-section of a wide screen box in which the inside of the springs and the supporting pipes are stationary.

105 Figs. 17, 18 and 19 are diagrams to illus-

trate various methods of application, the letter A representing the finest size the letter F the coarsest and intervening letters the next size in rotation.

5 Fig. 20 is a detail, showing a method of fastening fine screen cloth to the stretching beams.

Fig. 21 is a cross-section of a screen box 10 illustrating various stretching methods embraced in my invention.

The same part is designated by the same reference sign.

In the operation of vibrating screens, I have found that the longest life of the screen cloth, as well as the greatest capacity per square foot of screening surface and the least blinding of the screens is obtained when the screen cloth is stretched tight between the sides of a vibrating box, and 15 rigidly held to such box at the sides and ends only, allowing a clear unobstructed flow over the screening surface without bolts, rivets or other obstructions to hold the screen cloth to the vibrating member, 20 either longitudinally or crosswise of the screening surface. For example, I have tried the scheme of bolting the screen cloth to both longitudinal and cross beams placed in the screen box, but found that not alone 25 did such bolts interfere with proper screening, but the screen cloth wires near the bolts crystallized and broke long before the rest of the screen cloth was worn out. Steel beams used for this supporting purpose also 30 crystallized and broke near the bolt holes in a remarkably short time, but wood beams did not break, nor steel when reinforced by wood, or when rigidly held between wood frames.

35 I found also that where the sides of the screen cloth were rigidly held to a stationary frame, and the central part of the wire screen cloth was attached to a vibrating member, that not alone did the wires soon 40 break near the vibrating connection bolts, but the whole screen cloth wore rapidly where the wires were in contact with each other. Undoubtedly this was caused by the mechanical wrecking action and abrasion 45 due to the distortion of the position of the wires.

I therefore naturally reached the conclusion that the wires comprising the cloth must not be disturbed in relation to each 50 other, but must move in unison throughout the width and length of the screen cloth, and that the screen cloth should not be fastened to the vibrating member anywhere on the screening surface. Longitudinal connections to the center of the screen cloth 55 prevented the even distribution of the material to be screened, especially if the feed did not land exactly uniformly each side of such connections.

60 In my experience with vibrating screens,

I have found that the capacity of screens increases rapidly up to 2200 vibrations per minute on practically all kinds of and sizes of material and that beyond that point the capacity is not increased, but little, on very 70 coarse material, say above 1 or 2 inch size, nor is capacity increased very much at higher speed when handling moist, damp or sticky material, but when screening either all wet or all dry materials finer than 1 75 inch size, the capacity is increased to some extent up to 3300 vibrations per minute, and on fine dust even up to 4000 per minute, but beyond 4500 per minute, the capacity 80 rather falls down, possibly due to that gravity has not time to move the particles sufficiently downward through the meshes, before they are again thrown upward by the wires.

As a general rule, I operate my screens 85 from 2500 to 3000 vibrations per minute, and the vibrations may be about $\frac{1}{16}$ -inch diameter on fine material, $\frac{1}{8}$ " on medium size and $\frac{3}{16}$ " or slightly over on coarse as well as on moist material, on which less 90 number of vibrations and greater movement gives better results.

I have built the type of screen here shown in sizes from 1 ft. wide and 4 ft. long up to as large as 4 ft. wide and 16 ft. long 95 making as many as 7 sizes of products in one box, and it can be readily understood that to vibrate a screen of this latter size at the rates given, with at times as much as 1200 lbs. of a moving load on the screen, 100 is a serious problem, and can not be done without an unusual operating mechanism, and for this I employ an unbalanced pulley of a special design to assure cool running. I have found that any ordinary bearing 105 inside of 10 minutes run, under the severe conditions mentioned, will be smoking hot and melt babbitt, whereas with the construction shown, the pulley has run cool for over 200 hours, without replenishing the oil in 110 the pulley.

I have found the most efficient vibratory motion for screening to be a concentric or only slightly elliptic motion in a vertical plane.

115 In order to save valuable mill height, the motion should be differential or have a decided tendency to move the material forward from the head or feed end to the tail or discharge end of the screen. This allows 120 the use of less pitch or incline to the screen, than if only gravity is depended upon to move the material forward. On very accurate screening my vibrating screen can be operated on a level, or even up hill. The 125 screening is more rapid when the material moves in a thin stream over the surface than if it moves slowly. If gravity alone is utilized to move the material, then such a screen must be set very steep in order to thin 130

out the flow, but in such a case the gravity loses its screening ability as it is used up in transporting the material.

Contrary to popular opinion, it is gravity 5 and not the vibrations that accomplish the screening. The vibrations keep the oversize jumping up out of the way and clear the meshes, allowing the undersize to drop through the meshes from the force of 10 gravity.

I have observed that when a screen is overloaded, it may not actually screen through the meshes one-quarter as much material as when loaded slightly below 15 capacity. The cause is simple; the overload gives a deep bed of material through which the vibrations are not able to drive the oversize, some of which may stay still, in the meshes, so that the undersize cannot 20 drop through, hence the whole mass may slide down without being screened. Especially, is this true when handling an overload of moist and sticky material.

From experience, I have found that it is 25 necessary to provide a surplus of available power with corresponding resistance in a vibrating screen, so that, if any sudden rush in the feed supply (due to a temporary choke or other accident) the power is strong 30 enough to vibrate this overload.

By the use of more weight in the pulley and stiffer resistance springs than ordinarily are required to handle the usual load, the 35 overload is taken care of without using up but little more power than if just the right weight in pulley with correspondingly weaker springs were used to barely handle the regular load.

It naturally takes power to keep the 40 size in constant suspension, and on the move, hence the larger tonnage handled, the more power is required. But the unbalanced weight tries to revolve around its center of gravity against what resistance it meets, 45 hence if only small spring resistance were provided, the vibrations would be greater when underloaded or running idle, than when loaded to capacity or overloaded. Therefore, the vibrations must be of nearly 50 same amplitude under all conditions of load. Otherwise, they would become destructive to the life of the apparatus when underloaded and impotent when overloaded.

The screen box is made up of the sides 1, 55 to which are attached the top rails 2, and bottom rails 3, the head end 4, the tail end ties 5 and 6, the tie rods 7, the pipe struts 8 and the strut 9. Bolts 10 which pass clean through the bottom rail, 3, sides 1 and top 60 rails 2, serve to hold down pipe clamp 11 to the top rails 2; clamped fast in the pipe clamps 11 are supporting pipes 12 which have collars 13 shrunk on. To the ends of pipe 12 are pressed on the spiral springs 14, 65 which are held in place, by check nuts 15,

on the extreme end of pipes 12. The spiral springs 14 are clamped fast in the spring clamps 16 which are held rigidly by bolts 17 to the stationary supporting beams 18. It is immaterial if the exact order of fastening as here outlined is employed or if, as is 70 done in the largest screens, shown in Fig. 16, the spring clamp casting is bolted to the top rails 2 and the pipe clamps 11 are bolted to the supporting beams 18, in which case 75 the pipes 12 are stationary and the outside of springs 14 vibrate with the screen. As shown in Figures 1, 2, 3 and 4, the outsides of the springs 14 are stationary and the insides of the springs 14 and the pipes 12 80 vibrate with the screen. In the larger screens also, I usually provide a double set of springs to support the greater weight and still use same size springs with a large size pulley, indicated in Fig. 19. The only 85 reason for using pipes in place of solid rods is that the rods are more liable to crystallize and break than are pipes, and, especially on very wide screens, it would be impractical to use long rods that vibrated with the 90 screen box.

Bolts 19 pass clean through the rails and sides of screen box and serve to hold down shaft clamp 20 to the top rail 2. This clamp is placed a little nearer to the head end than 95 to the tail end of the screen box, so as to give the head end a greater effort than the tail end, because the load to be screened is greatest at the head end and besides the feed needs more violent shaking in the beginning 100 than later on, so as to stratify the finer material as soon as possible to the bottom of the mass to be screened. A hollow shaft 21 is clamped fast in shaft clamp 20. Plugs 105 22 serve to close up the ends of the hole 23 in the shaft 21. Near the end of the shaft is fastened a pipe nipple 24 that communicates with the hole 23. On the end of the nipple is a stop cock 25, screwed on. The upper end of the stop cock is plugged with 110 a removable plug 26.

From the outside of the shaft and communicating with hole 23, are drilled oil holes 27, 28 and 29.

On the surface of the enlarged part of the 115 shaft are oil grooves 30 cut right and left hand as shown in Fig. 9 and Fig. 15, where two oil scoops are used; or only right hand as in Fig. 12, where only one oil scoop is used.

On the shaft 21 is mounted an unbalanced pulley 31, having an anti-friction bushing 32 pressed into the hub of the pulley. This bushing has a free running fit on the shaft 21. The pulley has a crown face 33 in the center to receive the belt drive and flanges 34 on the ends, which form one side of the oil chambers 35, and also a pocket 36 in which weights 37 may be fastened, as for 125 example with set screw 38 and check nut 130

39 pushing the weight 37 up against pins 40. Caps 41 which are threaded on to the flanged part of the pulley complete the oil chambers 35. Gaskets 42 prevent oil leakage past the threads. In the hubs 43 of caps 41 are felt rings 44 to prevent dust and grit from entering the oil chambers. In the event that more oil has been put into the chambers than is necessary, these felt rings 10 also prevent the oil from leaking out from the oil chambers when the screen is standing still.

On the shaft 21 and enclosed inside the oil chambers 35 are fastened oil scoops 45, which communicate with the hole 23 by means of oil holes 27.

It is not necessary to use two oil scoops but only one serves the purpose fully as well, in the smaller size screens, and would be 20 just as well in the larger pulleys also. The diameter of the pulley is limited by the limit of belt speed, therefore, in some cases there is not room enough to make an oil return through the body of the pulley from 25 the one oil chamber to the other, which is necessary where only one oil scoop is used.

In Fig. 12 is shown the oil scoop 45 in the right hand chamber and in the left hand chamber is shown a set collar 46 to limit the 30 end play of the pulley. Return holes 47 through the body of the pulley put the two chambers in communication with each other, so that the oil which comes into the left hand chamber can return to the right hand chamber to be again picked up by the scoop.

In Fig. 13 the bushing 32 contains the holes 47, and the bushing is made out of balance in place of the body of the pulley.

In Fig. 14, the holes 47 are in the body of 40 the pulley, there being no holes for a distance of about 120 degrees, thereby making the pulley out of balance.

In Fig. 9 and Fig. 15, where two oil scoops are used, it is necessary that there is communication also between the two oil chambers, but here the communication is through the hollow shaft by means of hole 23. By means of this connection, the centrifugal oil level indicated by line 48, Fig. 10, remains 45 in balance. If there is more oil going back to one chamber than to the other, the centrifugal oil level will rise in that chamber, and consequently the oil pressure in that scoop is greater than in the opposite scoop, 50 which will then cease to pick up oil until the centrifugal levels in both chambers are alike.

When the construction shown in Figs. 12, 60 13 and 14, is used, the centrifugal oil level in the left hand chamber must of necessity rise to the return holes 47 and the centrifugal levels are not alike at both ends unless there is oil enough to fill both chambers up to the return grooves.

65 However, as a rule, only about enough

oil is put in to fill the chambers to the level line 49 (see Fig. 10), which indicates the oil level in both chambers when pulley is not revolving and this amount of oil will 70 form centrifugal levels 48 when pulley revolves. The line 49 is just below the shaft, and if chambers are only filled to that level, there can be no oil leakage when pulley is standing still, nor can there be any oil leakage when pulley is running even if filled 75 beyond level line 49. If oil enough is put in to merely fill the chambers, some oil will flow down the outside of the scoops to the shaft and the felt rings, and a slight oil leakage will continue until surplus oil is 80 eliminated. Undoubtedly there is some splash over the scoops that even at the lesser levels will reach the shaft and felt rings, and to prevent any leakage from that source, holes 85 50 connect the bottom of the felt grooves with the oil chamber.

The construction shown in Fig. 15, which is used on the wide screens, has three bearings.

The center bearing is necessary to prevent 90 heating of the end bearings. When only end bearings are used, the shaft evidently bends slightly under the vibrations unless it were made larger than is practical, but the pulley structure being practically of 95 pipe construction and of larger diameter, bends but slightly, hence there is a binding in the end bearings and they become very hot, but as a rule only one of them at a time. One day the left hand bearing may 100 run hot, and next day or hour it may cool down and the other run hot, and the cause for this erratic behavior I have been unable to discover. By putting in the center bearing and compelling both the pulley and 105 shaft to bend together, (if bend there is) the heating trouble is eliminated. The belt pull always being upward and the bending of the shaft naturally downward, more than in any other direction, also served to aggravate the heating of the end bearings, before the center bearing was introduced. With the single bearing construction and oil scoops 110 as shown in Figures 9 and 12, no hot bearings develop. In the construction shown in Fig. 12, the scoop end of the pulley is slightly warmer than the other end, and the construction shown in Fig. 9, develops slightly more heat than as in Fig. 12 and is evidently caused by the extra friction between the oil 115 and the second oil scoop.

I aim to proportion the pulley design so that the pressure per square inch of the oil (which by actual gauge test on medium size pulley has been shown to be 25 lbs. per 125 square inch, when running 2500 rev. per min.) multiplied by the projected bearing surface in square inches, will be considerably larger than the pounds centrifugal force developed by the unbalanced revolving weight 130

in the pulley. Thus the oil pressure keeps the metal surfaces of the bearings away from each other, or in other words it is a floating bearing.

The scoops are amply large to furnish more oil than can escape between the bushing and the shaft, thereby maintaining full oil pressure in the bearing at all times.

In the construction shown in Fig. 15, oil grooves 30 are only needed on the center bearing. The grooves are more for the purpose of conveying any grit or dirt that may be present in the oil or worn off from the bushing, so that the bearing will not be scored. Any grit that leaves the center bearing is caught in the cooling chambers 51 formed between the center bushing 32 and the end bushings 32, and held by centrifugal force to the outside of this chamber, thereby preventing the grit from entering the end bearings.

On account of being assured of clean oil for these bearings, oil holes 29 are not needed, nor desirable. The oil is cooler in the cooling chambers 51 than in the oil chambers 35, which are fed with oil coming directly from the end bearings, where most heat is produced. Some heat is also produced by oil friction against the outside of the oil scoops 45 in chamber 35. It will, therefore, be seen that oil should not be taken directly from the oil chambers 35 to the end bearings, but first through the cooling chambers. The oil pressure from the scoops and centrifugal force combined fill up the cooling chamber completely with oil, distributing the oil to all parts of the end bearing surfaces uniformly and gives better results than if the oil came out of holes in these bearings. As the shafts for large wide screens must of necessity be larger in diameter than for small and narrow screens, and still the pulleys must run at same speed in either case, it will be understood that the oiling system in the former must be still more perfect than in the latter.

In the one bearing pulleys the bushing 32 may be made in two pieces each somewhat less in length than half of the one full length bushing, thereby forming a chamber between the two, but the chambers would be so short that its practical value would be of small consequence.

In the construction shown in Fig. 13, it is impractical to make the bushing in two pieces, as the danger of the counter-weights not lining up perfectly would be too great.

It is necessary that the weights in the pulley be either exactly in line at both ends of the pulley or else placed exactly 180 degrees apart. In the narrow screens the weights are always in line; in the very wide screens, the weights in one end may be exactly 180 degrees apart from the weight in the other end, so that one end always moves

180 degrees behind the other. In the very wide screens the center of the screen cloth in spite of the stretching will vibrate further than the sides where the screen cloth is held to the vibrating box, and by putting the weights at 180 degrees apart in such a case the vibrations of the screen cloth may be made almost alike all over, for the reason that when weights are placed 180 degrees apart, the movement of the longitudinal center of the box is almost nil, but the longitudinal center of screen cloth under uniform motion will vibrate more than the sides.

When using the construction here described, there is no detrimental wrecking action produced on the wires from the 180 degree movement, because wires move with the box, and all parts of the wires are in the same still relation toward each other, and are not being distorted.

On narrow screens, it is detrimental to the screen action to have the movement 180 degrees apart, as the longitudinal center becomes inert.

The direction of the revolution of the pulley must be against the mouth of the oil scoop and upper side of the pulley must revolve toward the tail end of the screen box, as shown by arrows in the drawings.

The movement thus produced by the pulleys is lifting of the material on the head end and throwing it forward toward the tail end as this end drops. By actual trials, it has been demonstrated that when the pulley is revolved the other way (by turning shaft and all end for end) much of the material will pile up at the head end of the screen and actually travel back over the head board, even though the screen stands on an angle of 1 vertical to 2 horizontal.

When a card is taken of the motion, it is found that the motion of the screen box is not quite a circle, but slightly elliptical, the short axis in the direction of the length of the screen box. The weight of the apparatus and its load is balanced on the springs, but it takes power to move the material toward the tail end on any angle less than the angle of repose and therefore the resistance in the horizontal direction is undoubtedly greater than in the vertical direction.

The spiral springs 14, which support the screen box and allow it to vibrate with practically a concentric motion, are made so that the inner end bears for about $\frac{1}{3}$ of a turn on the second loop and the outer end bears for about $\frac{1}{3}$ turn on next to the last loop. The springs may be welded together where the loops come in contact, but this is usually not necessary except with the outside end, when the springs are mounted as shown in Fig. 16, where the motion of the screen box is applied on the outside of the springs, in which case there is a slight tendency to movement on the outside loop, which is en-

tirely prevented by welding before the springs are tempered. The inside loop is so stiff that no movement between the contact surfaces can be detected there, hence 5 welding there except in very large springs, is of doubtful value. Both the inside and outside ends are tapered in thickness, but not in width, thereby producing an even outside and inside surface. The hole or in- 10 side is concentric with the outside. The inside of the spring fits tightly on the supporting pipes 12, so that no movement or wear takes place there, nor is there any wear on the outside, which clamps fast in clamp 15 castings 16.

These springs are admirably adapted to accommodate a concentric movement. They are noiseless in action, no lubrication is needed or desirable; there is no wear or 20 movement between the springs and their contacts. The movement is all in the internal loops of the springs. No adjustments are needed to produce the required resistance. There is no chance for the operator to 25 alter its function and thereby make the screen inoperative. It requires the simplest kind of fastening only. The stationary supporting beams 18 may be placed below the supporting pipes 12 as shown in Figs. 4 and 30 5, or above as shown in dotted line 7, Fig. 4 and in Fig. 16.

The screen cloth 52 is fastened to stretching beams 53. Stretching bolts 54 serve to draw the beams 53 toward the sides 1 or 35 bottom rail 3, thereby pulling the screen cloth drum tight.

In case where wood is desirable for stretching beams, the construction shown in Fig. 4 is used. The edges of the screen cloth 40 are turned at right angles and the cloth held between cleats 55 and stretching beams 53, the cleats being screwed on to the beams, thereby clamping the cloth between the two. The turned sides of the cloth are also tacked 45 to stretching beams 53 in case of the finer cloth.

For stretching coarser and heavier cloth, steel channels and angles are more frequently used, as shown in Fig. 16 and in 50 more details in Figures 20 and 21, which show several variations, as for example, independent stretching at upper left hand and lower right hand, or twin stretching at lower left hand and upper right hand, all in Fig. 55 21. In case of independent stretching with angles spacers 56 are used. When channels are used, they in themselves form spacers.

Inside liners 57 serve to protect the sides 1 from wear, and also to hold down solidly 60 the stretching beams 53 to the bottom rails 3. The wedges 58 which bear against the top rails 2, serve to press down the liners 57. The wedges are not driven home solidly until the screen cloth is stretched.

65 When heavy screen cloth is used, it is only

necessary to bend the sides of the cloth over double or U-shaped, then slip the U over the flange of the channel or angle. When lighter cloth is used, I employ one or two U clips, one 59 fitting inside the other 60, 70 outside of the U shaped side of the screen cloth. This method effectually prevents slipping of the screen cloth when stretching, but also allows of easily slipping the flimsy screen cloth into place without removing the 75 stretching beams from the screen box. In case of very fine bronze and brass screens, I sometimes only use the inside U clip and solder screen cloth 52 to the inside U clip 59 as shown at 61, Fig. 2.

80 Where twin stretching is used in triple deck screens with sizes in tandem or more as shown in diagram, Fig. 1, the cloths cannot be slipped in when stretching beams are in position, but the screens must be put on to the beams outside the box and then dropped in place. In that case a nut 62 is riveted or welded to beams 53 and a tap bolt 63 employed for stretching. It would be impossible to put in bolts 54 in such a situation.

85 In operation, the pulley is belted to any convenient revolving power source and speeded to revolve about 2500 or 3000 rev. per min. in the direction shown by arrow. It does not matter at what angle the belt 90 comes to the pulley providing it clears the screen box. The material to be screened enters at the head end, (the right hand end of Figures 1-2 and 3). As a rule it does not pay to attempt to spread the feed perfectly 95 uniformly all over at the head end by means of mechanical feeders, as an ordinary spreading box and a foot extra length of screen serves the same purpose, as the feed almost immediately spreads over the full 100 width of the screen, to uniform thickness. Large enough weights 37 are added to give the desired intensity of vibration. Before starting enough light oil is put in through 105 the stop cock to fill the oil chambers to level line 49 which level can be determined by inserting a wire on the underside of shaft 21 and between felts 44; when the oil comes out alongside the wire, the chambers have 110 enough. The wire then of course is removed.

115 If it is desired to oil up while running, it is necessary to see that stop cock 25 is closed, then remove plug 26, and in its place screw in an oil gun, then open the stop cock and force the oil gun down; close the stop cock, remove the oil gun and replace the plug to keep sand out of the neck of the stop cock. If plug is removed and stop cock opened 120 while running the oil will squirt up to a great height and be lost in a few seconds.

125 There are no other adjustments except adding the proper size weights 37, and no other precautions except regarding the oiling while running. A few cubic inches of oil should be added about every 50 hours run.

- The machine gives a strong and intense vibration that screens materials at a very fast rate and the vibrations are not diminished by an overload. The pulley maintains a running heat of about 100 to 150 degrees Fahrenheit.
- Wet or dry screening can be handled, meshes do not clog and the machine requires no attention except oil once a week.
- Many variations and changes in the details of construction and arrangement would readily occur to persons skilled in the art and still fall within the spirit and scope of my invention. I do not, therefore, desire to be limited or restricted to the exact details shown and described.
- Having set forth the object and nature of my invention and various constructions embodying the principles thereof, what I claim as new and useful and of my own invention and desire to secure by Letters Patent, is:
1. In a vibrating screen structure, a screen adapted to support the material to be screened, coiled supporting springs for said screen, said spring coils disposed in a plane vertical to the screen surface, the whole weight of the screen being imposed on said coiled springs in a direction transverse to the axes of the coils thereof, and an unbalanced revolving member wholly and freely mounted to said screen to vibrate the same in vertical planes.
  2. In a vibrating screen structure, a screen, a stationary supporting frame, transverse screen supporting members for said screen, coiled springs on said members disposed between the same and the stationary supporting frame, the coils of said spring being disposed in a plane vertical to the screen surface, said spring coils being arranged to support the whole weight of the screen in a direction transverse to the axes of the spring coils thereof, and means wholly mounted on and carried by the screen to vibrate the same in vertical planes.
  3. In a vibrating screen structure, a screen, a stationary supporting frame, transverse members for said screen extending to said frame, involutely coiled springs on said members, the coils of said spring being disposed in a plane vertical to the screen surface, said spring coils being arranged to support the whole weight of the screen in a direction transverse to the axes of the spring coils thereof, and means mounted freely on and carried by the screen to vibrate said screen in planes vertical to said spring coils.
  4. In a vibrating screen, a screen element, a stationary element, supporting shafts disposed transversely with respect to said screen and stationary elements, and carried by one of said elements, coiled springs mounted on said shafts and interposed between said shafts and the other of said elements, said spring coils being adapted to vibrate in planes vertical to the plane of the screen element, and means wholly and freely mounted on the screen to vibrate said screen in vertical planes.
  5. In a vibrating structure, a vibratory element, a bearing shaft mounted on said element to vibrate with said element, a revolving pulley mounted on said shaft, an oil chamber, an oil scoop arranged therein, one of these members mounted to rotate with said pulley, an oil passage from the oil scoops to the bearings of said pulley, and means to return the oil from the pulley bearings to the chamber.
  6. In a vibrator structure, a vibratory element, a rotatable unbalanced element having bearings carried by the vibratory element, an oil chamber carried by one of said elements, means mounted within said chamber and carried by the other of said elements, and communicating with the bearings for said rotatable unbalanced element to distribute oil from said chamber to said bearings, and means to cause the return of the used oil from said bearing to said chamber.
  7. In a vibrator structure, a vibratory element, a rotatable unbalanced element having bearings, an oil chamber carried by one of said elements, oil delivery means mounted within said chamber and carried by the other of said elements, said chamber and said oil delivery means respectively communicating with said bearings, and means to maintain pressure within said chamber and bearings.
  8. In a vibrator structure, a vibratory element, a shaft, bearings therefor, said bearings carried by said vibratory element, a rotary member carried by said shaft, an oil chamber carried by said member and communicating with the said bearings, and means whereby the centrifugal pressure on the oil produced by the rotation of said chamber delivers the oil from said chamber to the shaft bearings, and means to rotate said member.
  9. In a vibrator structure, a vibratory element, a shaft carried thereby, and fixed rigidly thereto, a pulley device mounted to rotate upon said shaft, an oil chamber mounted to rotate with said pulley, means for distributing a lubricant mounted on said shaft and disposed within said chamber and communicating with the bearing surface of said pulley, and means to rotate said pulley.
  10. In a vibrator structure, a vibratory element, a shaft carried thereby, and fixed rigidly thereto, a pulley device mounted to rotate upon said shaft, an oil chamber mounted to rotate with said pulley, means for distributing a lubricant mounted on said shaft and disposed within said chamber and communicating with the bearing surface

of said pulley, means to return the excess oil from said bearing surface to said chamber, and means to rotate said pulley.

11. In a vibrator structure, a vibratory element, a stationary frame, shafts disposed adjacent each end of said vibratory element and extending transversely thereacross, and supported by said stationary frame, coiled springs mounted upon said shafts in a plane 10 vertical to the surface of said vibratory element and forming a yielding suspension for said vibratory element, a pulley journaled upon the vibratory element and extending transversely thereacross, means to rotate

said pulley, and means actuated by the rotations of said pulley for supplying a lubricant to the bearing surface thereof. 15

12. In a screen structure, a vibrating screen having supporting journals for its whole weight, coiled springs on said journals having axes disposed transversely of the screen, said screen being suspended upon said spring coils, and means supported freely on the screen to cause said screen to vibrate in a plane at right angles to the plane of 20 25 the screen.
